UNITED STATES PATENT OFFICE.

ADOLFO DE CLAIRMONT, OF TOLEDO, OHIO.

SELF-STARTING DEVICE FOR EXPLOSIVE-ENGINES.

1,120,797.

Specification of Letters Patent.

Patented Dec. 15, 1914.

Application filed February 8, 1912. Serial No. 676,387.

To all whom it may concern:

Be it known that I, ADOLFO DE CLAIRMONT, citizen of the United States, residing at Toledo, in the county of Lucas and State of Ohio, have invented certain new and useful Improvements in Self-Starting Devices for Explosive-Engines, of which the following is a specification.

My invention relates to self-starting devices for explosive engines, and more particularly to that type of self-starting device wherein fluid is admitted from a tank to the cylinder of the engine to operate the piston of the cylinder.

The primary object of my invention is the provision of a construction of this character whereby a small portion of gas, such as acetylene gas, may be drawn into the manifold of the engine during the last few revolutions of the engine at the moment that the spark switch controlling the ignition devices is turned off, thus causing a combination of atmospheric air, gasoline vapor, and a gas such as acetylene gas to form an explosive mixture in the manifold and enter each of the explosion cylinders. By causing such a combination of elements to enter the cylinders of the engine, it is easy for the driver to start the engine by simply switching on the battery and igniting the peculiarly explosive mixture that was introduced into the manifold during the last few revolutions of the engine.

A further object of the invention is to provide a device including a valve for controlling the passage of explosive fluid to the manifold as before stated, and provide in connection with the valve a handle so constructed that when released it will automatically shift to close the valve, thus obviating all danger of the valve being accidentally left open in case the driver should forget to shut off the valve.

A further object is to provide in connection with the valve and handle before described, means whereby the valve may be held open to permit the driver to crank the engine in case the car has lain idle for a number of hours and the cylinder is cool, or in case for any reason the engine will not start on the spark.

A further object is to provide in connection with the handle above referred to, a dial having thereon indicia indicating the various positions to be taken by the handle.

A further object is to provide means

whereby a proper amount of explosive gas may be drawn into the engine by the action of the engine itself, thus obviating any danger of injury to the engine and providing for the engine drawing in just enough gas for the purpose of compression and explosion, thus obviating the extra strain on the engine caused by the explosion of an ordinary mixture under pressure.

Other objects will appear in the course of the following description.

My invention is illustrated in the accompanying drawings wherein:

Figure 1 is a view partly sectional of the forward part of a motor car equipped with my improved self-starting device. Fig. 2 is a front elevation of the valve casing of the self-starting device. Fig. 3 is a section on the line 3—3 of Fig. 2. Fig. 4 is a section on the line 4—4 of Fig. 2.

Corresponding and like parts are referred to in the following description and indicated in all the views of the accompanying drawings by the same reference characters.

In the drawing, A designates a motor car of any suitable construction and provided with the dashboard 2. The cylinders of the engine are designated 3. There may be of course as many cylinders as desired. I have illustrated however, only two cylinders, these cylinders being connected by a manifold 4 with a carburetor 5. The particular form of carburetor or manifold forms no part of my invention.

Mounted upon the dashboard 2 is a valve casing designated 6 and illustrated in detail in Figs. 2, 3 and 4. This valve casing is preferably made of brass and is preferably circular in form, though not necessarily so. The valve casing is shown as formed with a base plate 7 having outwardly extending flanges 8 to which the body of the valve casing is attached.

Disposed within the valve casing 6 is a tapered barrel 9 connected at opposite points in its diameter with inlet and outlet pipes respectively. The inlet pipe designated 10 leads from a gas tank 11 which is shown as the ordinary acetylene gas tank usually found upon motor cars. This pipe 10 is connected to the gas tank in any suitable or ordinary manner. The outlet pipe 12 extends out through the rear of the casing and connects to the manifold 4 in the manner shown in Fig. 1. Preferably the inlet pipe 10 also extends through the dashboard 2

and then extends downward as illustrated in Fig. 1 to connect with the pipe leading from the gas tank 11. Thus these pipes 10 and 12 are fully protected by the hood which incloses the engine.

Disposed within the barrel 9 is a tapering valve plug 13 as illustrated in Figs. 3 and 4 formed with a transversely extending port or passageway 14 opening on diametrically opposite sides of the plug. Engaging the plug and drawing it to its seat is a set screw 15 which extends out through the valve casing, and carried upon this screw 15 which forms a spindle projecting from the valve and moving with it is an arm 16 forming a handle, this arm being extended beyond the screw 15 or spindle so as to form a pointer 17. The other end of the arm opposite the pointer is extended beyond the valve casing and is provided with a weight 18. The handle 16 is so arranged with relation to the valve 9 that the handle extends in the same direction as the passage 14 of the valve plug. It will be seen that the pipes 10 and 12 are horizontally arranged opposite each other, and that the normal position of the pointer or handle 16 is vertical and that therefore normally the passage 14 does not connect the pipes 10 and 12, but that when the handle 16 is rotated to a horizontal position as indicated in Fig. 4, then the port 14 connects the pipes 10 and 12 and gas may pass from the acetylene gas tank 11, through the valve 9 to the manifold 4. It will also be noted that the weighted end 18 of the handle 16 tends to return the handle to its vertical position unless it is held in a horizontal position.

For the purpose of holding the arm 16 in its horizontal position, I provide coacting means disposed upon the handle and upon the valve casing 6 whereby the handle may be detachably engaged and supported in its horizontal position. The particular means shown by me comprises a spring 19 disposed within the valve casing and having a projecting stud 20 at its end which extends out through an opening in the valve casing. The inner face of the arm or handle 16 is formed with a recess 21 with which the stud 20 is adapted to engage when the handle is turned to its horizontal position. This engagement however is so relatively light that a very slight manual movement of the handle will cause the release of the stud 20 and permit the handle to drop to its normal position.

For the purpose of holding the handle or arm 16 in its normal or vertical position, I also provide a spring 22 which is attached to the inside face of the valve casing and which carries at its end an outwardly projecting stud 23 which extends through the face of the valve casing and engages the shallow recess 21 previously referred to. The purpose 60 of this detaining means last described is

simply to yieldably hold the handle in its vertical or normal position and thus prevent it from being oscillated by the jar and jolts incident to running the motor car to which the device is applied.

The face of the case 6 is preferably provided with indicia indicating the positions to which the handle is to be moved in order to properly operate the device. The word "Closed" is provided upon the face plate of the casing 6 at the upper portion of the face plate, the pointer normally pointing to this word "Closed." The face plate is provided on its left hand margin with the words "Open for spark" which are arranged adjacent to the projection of the stud 20. Opposite the words "Open for spark" the face plate of the casing is provided with the words "Open for cranking." The pointer 17 carried upon the handle or arm 16 is designed to coact with these words to indicate the position of the valve within the casing. Thus when the pointer 17 is turned to the word "Closed," it means that the valve is in the position shown in Fig. 3, that is, that communication between the acetylene gas tank and the manifold 4 is entirely cut off. When the pointer is turned toward the words "Open for cranking," it means that communication is established between the acetylene gas tank 11 and the manifold 4. When the pointer 17 is turned to the words "Open for spark," communication is also established between the gas tank 11 and the manifold 4.

It is to be particularly noted that when the pointer is turned to the words "Open for spark," the handle 16 is not supported in its horizontal position and that it must be held in this horizontal position. As soon as the handle is released, it will drop back to its vertical position and cut off communication between the acetylene gas tank and the engine cylinder. When, however, the pointer is turned to "Open for cranking," then the handle 16 is engaged with the stud 21 and the valve is held open until manually closed. The reason for this construction is as follows: When the operator intends to stop his engine and turns off the switch of the sparking devices, he turns the handle to a horizontal position with the pointer extending toward the words "Open for spark." The last few revolutions of the engine before it stops therefore draws into the manifold a combination of atmospheric air, gasoline vapor and acetylene gas which forms an extremely explosive mixture. This explosive mixture enters the manifold and each of the gas cylinders. With this extremely explosive mixture in the gas cylinders it is easy for the driver to start his engine again by simply switching on the battery. As soon as the engine stops, after having drawn in the acetylene gas into the

manifold, the operator releases the handle 16, whereupon the handle will drop to its vertical position with the pointer extending toward the word "Closed." The apparatus is then ready for being started by simply switching in the ignition devices. Where the engine has lain idle for some time, however, and the cylinders as a consequence have gotten cold, it is necessary that a charge of fresh acetylene gas together with gasoline and air should enter the cylinders, and it is necessary that the valve 9 be held at such position as will permit the entrance of the fresh charge while the operator is cranking the engine, with the sparking devices however thrown out. Under these circumstances the operator turns the handle to such position that the pointer will extend toward the words "Open for cranking," whereupon the stud 23 will engage the handle and hold it in its horizontal position with the valve open. The operator then without turning on the switch of the ignition devices cranks the engine or turns it over two or three times so as to draw in a fresh charge of acetylene gas, gasoline and air into the cylinder. After the operator has cranked the engine, he manually actuates the handle 16 and returns it to its closed position. Then by switching in the igniting mechanism the engine may be started by simply igniting the highly explosive gas in the cylinders.

By removing the set screw 15^a which enters the spindle 15, it is possible to take off the needle and handle and pull out the valve 9 at 10, thus permitting the valve to be cleaned and regulated.

It will be obvious that the casing 6 might be dispensed with as the casing itself merely protects the inclosed mechanism and provides a support for the dial 6^a which forms the outer face of the casing. By inclosing the parts within the casing however they are rendered free from accidental derangement.

In connection with this device, I provide a reducing valve designated 24 which is attached to the tank 11 whereby the pressure of the gas may be reduced to any desired extent. By means of my improved valve it is possible to introduce into a cylinder a proper amount of explosive gas by the action of the engine itself, the engine regulating the amount of gas so introduced so that only enough gas is introduced as to be sufficient for its purpose, whether it is combined with acetylene gas and gasoline, or whether it is pure acetylene gas, and this without any danger of injury to the engine. The reason for this is that the cubical content of the engine cylinders is such that on the suction stroke of the engine, just enough gas will be taken up for the purpose of compression and explosion. In

other devices known to me wherein an explosive gas is introduced directly into the cylinders of the engine, the additional gas so introduced is wasted, inasmuch as the engine is already charged and loaded with its explosive mixture or compound at the time that the explosive gas is introduced.

My self-starting device is also particularly advantageous inasmuch as in starting the engine by means thereof, there is no strain upon the engine. If the engine does not start on the spark on account of stopping at a center or for any other reason, the engine will not start on another cylinder and back fire as frequently happens when gas is introduced into all of the cylinders by means of connections extending directly to the cylinders. This back-fire causes considerable injury to the engine and strains the cylinder. It also causes waste of gas.

My invention permits only just enough acetylene gas to enter the cylinders to start the same, and I have also found that my device makes it far easier to start on the spark than with the ordinary type of self-starter, even though hours have passed after a car has come to a standstill. It is possible with my device to start a car on a single turn of the crank on account of the fact that the acetylene gas drawn in and compressed on the one turn of the crank is far more expansive on account of being mixed with gasoline than if this acetylene gas is introduced into an engine which already has received its charge of gasoline and air under compression. With my invention it is perfectly easy to start on the spark without failure and without danger of back-fire, provided the engine is turned over once or twice before turning on the spark.

It will of course be understood that I do not wish to be limited to the precise details of the invention illustrated. Thus the form of the casing or dial over which the handle moves may be changed as desired. The exact form of the casing may be changed, and it will be obvious that other forms of reducing valves may be introduced than that illustrated.

What I claim is:

1. Means for controlling the passage of gas to an explosive engine, including a conductor for the gas, a rotatable valve disposed in the conductor, a weighted handle on the valve, and a pointer movable with the valve.

2. Means for controlling the passage of explosive gas to an explosive engine, comprising a conductor, a rotatable valve in the conductor movable to cut off or establish communication through the conductor, a spindle on the valve, a weighted handle extending from the spindle, a pointer connected to the handle, and means disposed in conjunction with the handle for yieldingly sup-

- porting the handle and valve in a position to permit the passage of gas.
3. Means for admitting explosive gas to an explosive engine, including an conductor, a rotatable valve in the conductor, a dial, a spindle on the valve projecting through the dial, a handle on the spindle, a pointer projecting from the handle and movable over the dial, and means on the dial 10 yieldingly engaging the handle to hold it in an adjusted position.
4. Means for admitting explosive gas to an explosive engine, comprising a conductor, a rotatable valve in the conductor having a diametrically extending passageway whereby said valve is rotatable in opposite directions through a half circle to establish communication through said conductor, a weighted handle on the valve normally holding the valve in position to disestablish said communication, and means engaging the handle for yieldingly holding the valve in one of the positions where it establishes communication through said conductor.
5. The combination with the cylinder of a gas engine, a carbureter and a conductor leading from the carbureter to the cylinder, of a tank containing explosive gas, a pipe leading from the tank to said conductor, a rotatable valve in said pipe having a diametrically extending passage adapted when the valve is in one position to cut off communication through the pipe and when the valve is in another position to establish said communication, a spindle on the valve, a weighted handle on the spindle, said handle extending parallel to the passage through the valve, and therefore holding the valve in a position to cut off communication, and yielding means disposed in the path of the handle for supporting the handle against the force of gravity in position to bring the passage through the valve in alignment with said pipe.
6. Self-starting mechanism for explosive engines, including a conducting pipe leading from a source of gas, a rotatable valve within the pipe having a diametrical passageway, a dial, a handle on the valve extending parallel to the dial and parallel to the passageway through the valve, said handle being weighted, means yieldingly projected
- through the dial for holding the handle in a vertical position, and yielding means projected through the dial for holding the handle in one of its horizontal positions.
7. Self-starting mechanism for explosive engines, including a conductor leading from a source of gas supply, a rotatable valve mounted in the length of said conductor and having a diametrically extending passageway, a weighted handle on said valve extending at right angles to the axis of the valve and parallel to the passageway through the valve, a dial over which said handle moves, a pointer carried by the handle, indications upon the dial designating a closed position for the handle and pointer, diametrically opposed designations on the dial for indicating positions of the pointer corresponding to the two positions wherein the valve will establish communication through the conductor, and means in conjunction with one of said indications on the dial for yieldingly supporting the handle and valve in position to establish communication through the conductor.
8. In self-starting mechanism for explosive engines, a conductor, a rotatable valve disposed in the length of the conductor, a weighted handle projecting from said valve and having a socket formed in its inner face, and a resiliently projected stud yieldingly engaging the handle to hold it in a designated position.
9. Means for controlling the passage of explosive gas to an explosive engine comprising a conductor, a valve in the conductor movable to cut off or establish communication through the conductor, a spindle on the valve, a handle extending from the spindle, a pointer connected to the handle, means yieldingly urging the valve to a closed position, and means disposed in conjunction with the handle for yieldingly supporting the handle and valve in a position to permit the passage of gas.

In testimony whereof I affix my signature in presence of two witnesses.
